MOTORIZED WATER-JET VEHICLE

Harold A. Price, Orange, Calif., assignor to Alfred S. Bloomingdale

Filed May 23, 1966, Ser. No. 2,454

Term of patent 14 years

(Cl. D71—1)

FIG. 1

FIG. 2

FIG. 3

FIG. 4

FIGURE 1 is a plan view of a motorized water-jet vehicle showing the new design;

FIGURE 2 is a left side elevational view thereof;

FIGURE 3 is a rear elevational view thereof; and

FIGURE 4 is a perspective view thereof taken from an upper forward quarter.

In view of the prior art, the characteristic feature of my design resides in the overall appearance resultant from the combination of the general overall shape and the specific flattened-oval cross-sectional shape, producing a basically curvilinear design.

I claim:

The ornamental design for a motorized water-jet vehicle, substantially as shown and described.
